UNITED STATES PATENT OFFICE.

EMIL G. SAUER, OF BROOKLYN, NEW YORK, ASSIGNOR TO THE LOWELL
MANUFACTURING COMPANY, OF MASSACHUSETTS.

DESIGN FOR CARPET.

SPECIFICATION forming part of Design No. 24,845, dated November 5, 1895.

Application filed August 31, 1895. Serial No. 561,159. Term of patent 3½ years.

To all whom it may concern:

Be it known that I, EMIL G. SAUER, a citizen of the United States, and a resident of Brooklyn, in the county of Kings, State of New York, have invented a new and original Design for Carpets and Borders, (known as Pattern No. 5,096,) of which the following is a specification.

This invention comprises two parts—namely, the design A for a carpet, and the design B for a border; and I do hereby declare that the drawing accompanying this specification conveys to any one a clear understanding of the same, and is sufficient to enable such person to use my invention.

The design A is characterized by small scattered leaf and flower forms, the same constituting its leading feature.

The design B is characterized by festoons

of leaf and flower forms and festoons of lace-work, the two being intertwined, the same constituting its leading feature.

What I claim, and desire to secure by Letters Patent, is—

1. In a design for a carpet, the body A, substantially as shown.
2. In a design for a carpet, the border B, substantially as shown.
3. The design for a carpet, comprising the body A and border B, substantially as shown.

In testimony whereof I have signed my name to this specification in the presence of two subscribing witnesses.

EMIL G. SAUER.
